UNITED STATES PATENT OFFICE

WILLIAM A. FRENCH, OF MINNEAPOLIS, MINNESOTA, ASSIGNOR TO WM. A. FRENCH
FURNITURE CO., OF MINNEAPOLIS, MINNESOTA

DESIGN FOR A DRESSING TABLE

Application filed April 3, 1929. Serial No. 30,736. Term of patent 3½ years.

To all whom it may concern:

Be it known that I, WILLIAM A. FRENCH, a citizen of the United States, residing at Minneapolis, in the county of Hennepin and State of Minnesota, have invented a new, original, and ornamental Design for Dressing Tables, of which the following is a specification, reference being had to the accompanying drawing, forming part thereof.

The figure is a perspective view of a dressing table, showing my new design.

I claim:

The ornamental design for a dressing table, as shown.

In testimony whereof I hereunto affix my signature.

WILLIAM A. FRENCH.
